UNITED STATES PATENT OFFICE.

FRED E. WHEATON, OF MINNEAPOLIS, MINNESOTA.

DESIGN FOR A BADGE OR BUTTON.

50,455.

Specification for Design.

Patented Mar. 13, 1917.

Application filed October 2, 1915. Serial No. 53,849. Term of patent 14 years.

To all whom it may concern:

Be it known that I, FRED E. WHEATON, a citizen of the United States, residing at Minneapolis, in the county of Hennepin and State of Minnesota, have invented a new, original, and ornamental Design for a Badge or Button, of which the following is a specification, reference being had to the accompanying drawing, forming a part hereof.

This invention has for its object to provide a novel and ornamental design for a badge or button.

Copies of this patent may be obtained for five cents each, by addressing the "Commissioner of Patents, Washington, D. C."

The accompanying drawing shows an elevation of a badge or button embodying my design.

I claim:

The ornamental design for a badge or button as shown.

FRED E. WHEATON.
